UNITED STATES PATENT OFFICE.

PHILIP BRAND, OF NEW YORK, N. Y.

SHAPER AND FORM-HOLDER FOR HATS.

1,372,668.

Specification of Letters Patent. Patented Mar. 29, 1921.

Application filed December 31, 1919. Serial No. 348,551.

To all whom it may concern:

Be it known that I, PHILIP BRAND, a citizen of the United States, residing in the borough of Bronx, county of Bronx, and 5 State of New York, have invented a new and useful Improvement in Shapers and Form-Holders for Hats, of which the following is a description.

This invention has reference to devices for 10 shaping and holding the form of soft felt hats and, particularly, relates to an adjustable means by which the hat may be shaped and its form held, and many other advantages are obtained therefrom not possible in 15 prior art structures.

Among the objects of my invention may be noted the following: to provide a device which may be applied to soft felt hats, and which will give thereto the desired shape or 20 form, which latter can be held or maintained during the entire use of the device; to provide an adjustable device by which the shape given to the hat may be varied within certain limitations; to provide a device of the 25 character set forth in the foregoing which will not crease the hat, but which will give thereto a well rounded and graceful form; to provide a device for shaping, and holding the shape of, felt hats which will not crack 30 the felt and which will stay in the position given it without injuring the material of the hat; to provide a hat shaper and form holder with means by which a good grip can be obtained upon the hat for removing and re- 35 placing the same when desired, and which prevents crushing the hat in handling, and which prevents the latter from losing its form; to provide means by which the branches of the device are strengthened and 40 the material of the hat can be bent around said branches, so as to give the graceful indentations to the sides of the hat which are desired; and to provide a simple, strong, durable, effective and economical device for 45 performing the functions and carrying out the objects set forth in the foregoing.

In order that my invention may be clearly understood, I have provided drawings wherein:

50 Figure 1 is a side elevation of my improved hat shaper and form holder;

Fig. 2 is an end elevation of Fig. 1; and

Fig. 3 is a cross-section of a felt hat of conventional form showing my shaper and 55 form holder in position, this figure being

shown broken away on one side owing to the limitations of the sheet.

Referring to the drawings, Figs. 2 and 3, it will be seen that my device has the general form of the letter Y. This is important 60 from several standpoints: first, because it gives the desired and proper form to the soft felt hats now in use; secondly, because it provides branches which hold the form and shape the hat as desired; and, thirdly, because the branches can be adjusted relatively 65 so as to vary the spread to the indentation and vary the height of the crown of the hat.

In all the figures of the drawings, the numeral 1 indicates the stem or base member 70 of the form holder and shaper, which is made U-shaped in cross-section for the purpose of providing a receptacle of large capacity into which the fold 2 of the crown of the hat may be depressed, it being particularly noted that this fold is not creased, and that the base of my shaper is purely a receptacle capable of receiving the fold of soft 75 felt hats, regardless of the weight of the material. The base or stem 1 of the device 80 is centrally located and has, at each end thereof, a pair of tongues 3 which are indent or incurved to engage gently, but sufficiently, the body of the fold 2 of the hat which passes between the same, and which tongues grip 85 the fold at a considerable distance above its extremity or ridge. The tongues 3 are flexible and can be bent more or less one way or the other, so as to vary the pressure thereof upon the material of the fold. Being ar- 90 ranged at opposite ends of the device, as shown in Fig. 1, the tongues 3 grip the fold 2 of the hat uniformly and at equal distances from the base 1 of the device, thus properly supporting the shaper within the hat and 95 upon the fold, with no tendency to alter its position at either end.

The branches 4 of the shaper are flared outwardly from the top of the stem and, at their extremities, are curled outwardly, as at 100 5, into cylindrical form. The material of the shaper being flexible, the branches 4 can be varied in position relatively to each other, so as to give to the fold at the crown of the hat a more or less widespread position, as 105 shown, for example, in Fig. 3; and the extremities being curled or rolled over, as at 5, shape the hat at the crown symmetrically, avoiding creasing and cracking and having the function of holding the crown of the 110

hat in proper position. By rolling into cylindrical form the extremities 5, the said extremities are strengthened, and the latter, in turn, strengthen the branches 4, preventing the latter from being flexed out of proper form. Again, the rolled extremities 5 provide a substantial and extensive means by which to grip the hat at the crown, enabling the wearer to readily and freely 10 handle the same for removing and replacing, and for doffing the same, as required, without crushing the crown or causing the hat to lose its shape or form. Furthermore, by rounding the extremities, the sides of 15 the hat can be bent inwardly, as at 6, thus giving the graceful and ornamental shape and indentation, so desirable in soft hats, and this shape is permanently held or maintained, due to the shape of the form holder 20 and to the round extremities 5 thereof.

While I have shown the extremities 5 curled or rolled into the form of a cylinder, I desire it distinctly understood that said extremities may be varied in shape and extent, without departing from the spirit of 25 my invention or depriving it of its characteristics as hereinbefore set forth. I, preferably, make my shaper and form holder of light metal such as aluminum, which is not only flexible, but has, or can be given, a certain amount of resiliency, enabling it to be 30 handled without changing its form. I do not wish to be limited, however, to such metal, or to any metal; but, desire it understood that I may make the device of any 35 flexible or resilient material found suitable for the purpose. It will be seen, also, that I

have made my device of a single sheet of material, and it will be readily understood that the same can be blanked out of sheet 40 metal or other material and the form given thereto, as shown in Figs. 2 and 3, by simple operations.

Having thus described my invention, what I claim and desire to secure by Letters 45 Patent is:

1. A shaper and form holder for soft hats comprising a piece of sheet material formed into a U-shaped base member affording a receptacle for the fold of the hat; a pair of 50 branched arms terminating in cylindrical extremities for supporting the crown of the hat; and inwardly bent tongues or members for engaging the fold of the hat beyond the base of the device. 55

2. A hat shaper and form holder made of a single piece of sheet material having a U-shaped central base member; a pair of inwardly bent holding members at opposite ends of the base member; and a pair of 60 branched arms terminating in crown-supporting devices.

3. A shaper and form holder for soft hats comprising a receptacle for the fold of the hat, and a pair of outwardly branched arms 65 terminating in stiff cylindrical members for supporting the crown of the hat, the receptacle being shorter than the said members, and tongues extending inwardly from said members at opposite ends of the receptacle 70 and separated therefrom for engaging the hat above the fold.

PHILIP BRAND.
